United States Patent Office

Des. 208,900
Patented Oct. 17, 1967

208,900

GIRDLE

Sallyann Z. Salisky, Garfield, N.J., assignor to Sarong,
Inc., Dover, Del., a corporation of Delaware

Filed Apr. 13, 1966, Ser. No. 1,872

Term of patent 14 years

(Cl. D2—2)

— FIG. 3.

The essential features of my design reside in the full line disclosure on the drawing.

I claim:

The ornamental design for a girdle, as shown and described.
